[57] CLAIM

The ornamental design for an antenna structure for detecting antitheft tags in a retail establishment, as shown and described.

DESCRIPTION

FIG. 1 is a front view of a first embodiment of the an antenna

structure for detecting antitheft tags in a retail establishment, the rear view being a mirror image thereof;

FIG. 2 is a perspective view of the first embodiment of the an antenna structure for detecting antitheft tags in a retail establishment;

FIG. 3 is a top view of the first embodiment of the an antenna structure for detecting antitheft tags in a retail establishment;

FIG. 4 is a right side view of the first embodiment of the an antenna structure for detecting antitheft tags in a retail establishment, the left side view being a mirror image thereof;

FIG. 5 is a bottom view of the first embodiment of the an antenna structure for detecting antitheft tags in a retail establishment;

FIG. 6 is a front view of a second embodiment of the an antenna structure for detecting antitheft tags in a retail establishment, the rear view being a mirror image thereof;

FIG. 7 is a perspective view of the second embodiment of the an antenna structure for detecting antitheft tags in a retail establishment;

FIG. 8 is a top view of the second embodiment of the an antenna structure for detecting antitheft tags in a retail establishment;

FIG. 9 is a right side view of the second embodiment of the an antenna structure for detecting antitheft tags in a retail establishment, the left side view being a mirror image thereof; and,

FIG. 10 is a bottom view of the second embodiment of the an antenna structure for detecting antitheft tags in a retail establishment.

UNITED STATES PATENT AND TRADEMARK OFFICE
CERTIFICATE OF CORRECTION

PATENT NO. : Des. 377,768
DATED : February 4, 1997
INVENTOR(S) : Anthony C. DOUGLAS

It is certified that error appears in the above-identified patent and that said Letters Patent is hereby corrected as shown below:

On the title page, line 1 under the DESCRIPTION section, after 'the' delete "an".

On the title page, lines 4-5 under the DESCRIPTION section, after the second occurrence of 'the' delete "an".

On the title page, line 7 under the DESCRIPTION section, after the second occurrence of 'the' delete "an".

On the title page, line 10 under the DESCRIPTION section, after the second occurrence of 'the' delete "an".

On the title page, line 14 under the DESCRIPTION section, after the second occurrence of 'the' delete "an".

On the title page, line 17 under the DESCRIPTION section, after 'the' delete "an".

On the title page, line 21 under the DESCRIPTION section, after 'the' delete "an".

On the title page, lines 23-24 under the DESCRIPTION section, after the second occurrence of 'the' delete "an".

UNITED STATES PATENT AND TRADEMARK OFFICE
CERTIFICATE OF CORRECTION

PATENT NO. : Des. 377,768
DATED : February 4, 1997
INVENTOR(S) : Anthony C. DOUGLAS

It is certified that error appears in the above-identified patent and that said Letters Patent is hereby corrected as shown below:

On the title page, lines 26-27 under the DESCRIPTION section, after the second occurrence of 'the' delete "an".

On the title page, lines 30-31 under the DESCRIPTION section, after the second occurrence of 'the' delete "an".
